UNITED STATES PATENT OFFICE.

EZECHIEL WEINTRAUB, OF LYNN, MASSACHUSETTS, ASSIGNOR TO GENERAL ELECTRIC COMPANY, A CORPORATION OF NEW YORK.

VAPOR ELECTRIC DEVICE.

1,075,615.

Specification of Letters Patent.

Patented Oct. 14, 1913.

Application filed April 3, 1911. Serial No. 618,659.

To all whom it may concern:

Be it known that I, EZECHIEL WEINTRAUB, a citizen of the United States, residing at Lynn, county of Essex, State of Massachusetts, have invented certain new and useful Improvements in Vapor Electric Devices, of which the following is a specification.

My invention relates to vapor electric devices, such as mercury vapor lamps, and particularly to a type of mercury vapor device described in my previous Patent #917,212, in which an arc plays in an inner envelop of quartz or other refractory material. Its 15 principal object is to provide a container which is simple in structure and which can be started readily without a possibility of the arc being struck through the space surrounding the inner envelop.

Other features of my invention relate to 20 details of construction.

One feature of my invention involves a construction of the device which provides that the mercury or other electrode material 25 outside of the inner tube recedes out of electrical connection with the leading-in conductor when the device is tilted before it comes in contact with the other leading-in wire as the mercury flows from one electrode to another. Therefore, when the device is tilted 30 back to its original position, the arc will invariably be struck through the inner tube inasmuch as no circuit is ever established by the mercury outside the same. Another 35 feature of construction makes provision for readily starting the device.

Figure 1 in the accompanying drawing is a longitudinal section of the mercury arc lamp having mercury electrodes and constructed in accordance with my invention; Fig. 2 is a cross-sectional view taken on the line 2-2; Fig. 3 is a cross-sectional view of a lamp having an inner tube of slightly modified shape; Fig. 4 is a longitudinal section of a lamp having a mercury cathode and a solid anode; Fig. 5 is a cross-section taken on the line 5-5; Fig. 6 is a longitudinal section of a modified construction, Fig. 7 being the corresponding sectional view; Fig. 8 is a diagram of electrical connections for the tilting mechanism and Fig. 9 illustrates a modified form of lamp.

Referring to Fig. 1 the outer container 1 consists of transparent material as glass and

is provided with an inner envelop 2 of quartz 55 or other highly refractory, transparent or translucent material. Openings are provided in the inner tube in order to allow the same to be easily evacuated, and to permit the return of vaporized electrode material. 60 These openings in Fig. 1 are represented by the openings in the electrode chambers and the opening indicated at 3. As indicated in the drawing each end of the device is bent at an angle so as to form pockets for bodies of 65 mercury forming the electrodes of the device. Contact is made with the body of mercury forming cathode 4 by means of a chain 5 of platinum, tungsten or other heavy metal which does not readily alloy with mercury. 70 When the device is assembled this chain is slipped through the opening 6 in the cathode chamber. Its flexibility insures electrical contact at all times with the mercury. Contact is made at the anode end by means 75 of the platinum wire 7 projecting into the body of mercury 8 through a reentrant portion of the quartz envelop, thereby insuring that the arc will at all times be struck with the mercury and not run to the platinum 80 wire.

The space intervening between the inner and outer envelop is so proportioned, and the openings in the inner tube are so positioned that when the tube is tilted to start 85 the arc by appropriate mechanism, that a portion of the wall of the inner tube will break the continuity of the electrical circuit of the receding body of mercury outside the inner envelop and the adjoining electrode 90 before the mercury stream flowing outside the tube has come into contact with the other electrode. This construction avoids the possibility of the completion of the electrical circuit by the mercury outside the inner tube. The mercury inside the tube, however, does complete the electrical circuit 95 when the tube is tilted. As the tube is tilted back the interruption of the circuit starts the arc. The arc a short time after it is 100 started ceases to fill the entire space within the inner tube and concentrates itself at its center, taking up perhaps one-third to one-half of the cross-section of the tube.

I have discovered that when part of the inner tube is made V-shaped in cross-section, the arc will continue to pass through the center of the tube. The position of the arc

will not tend to be depressed by the groove provided by this construction. I have taken advantage of this fact by shaping the tube as shown, for example, in the cross sectional views Figs. 2 and 3, with a groove or trough along its lower side to facilitate the flow of mercury within the tube from one electrode to the other. It will be observed that this construction lowers the path of mercury flow while still retaining the central position of the arc within the device. Consequently it is necessary to raise the mercury level at electrode 4 only a very little to cause the mercury to flow along the groove to the other electrode. Briefly, this construction is accompanied with the advantage of requiring but a very slight tilt to start the arc without allowing the latter, when fully established, to overheat the lower part of the outer glass tube as would be the case if a round inner tube were merely lowered, or placed closer to the lower surface of the outer tube. Spacing off-sets 9 support the tube 2 and keep it out of contact with the outer glass tube 1.

It will be observed that the construction of my improved form of device renders the starting of the arc inside the quartz tube easy and certain and precludes the possibility of the starting of the arc outside the same.

The construction shown in Fig. 4 is very similar to the construction already described in connection with Fig. 1 except that in this case the lamp is provided with a solid anode 10. The construction of the cathode end of the lamp is similar to that already described in connection with Fig. 1. The lamp may be provided with a platinum wire leading-in conductor 11 instead of the small chain shown in Fig. 1. The leading-in conductor 12 at the anode end making contact with electrode 10, is sealed into the glass wall of the outer envelop and extends through the quartz envelop 2. It may be surrounded as a special precaution by a small quartz tube 13. However, even when thus surrounded, a very small portion of the leading-in wire would be exposed at the joint, and there is some danger of the arc forming between the wire as anode and the mercury in the annular space outside the inner envelop unless provision were made in the construction of the device as already described above, for breaking electrical contact between the mercury in this annular space and the source of current when the tube is tilted. The inner tube is likewise provided with a depressed trough as already described and as more clearly shown in Fig. 5. The anode 10 may be provided near its end by an annular disk 14 in order to facilitate proper contact between it and the stream of mercury flowing toward the anode 65 when the lamp is started. The anode cham-

ber is provided with an opening 15 for the purpose of exhausting the tube and as a pressure equalizing means.

The construction of Fig. 6 is in most respects similar to that already described in connection with Figs. 1 and 4, but the construction at the anode end of the lamp is somewhat simpler inasmuch as an open ended tube is used dipping into the mercury, contact with which is made at the lower end by means of a wire 16. While this form of lamp has not been shown as provided with the depressed trough or groove in the inner tube through which the mercury may flow, its construction in other respects is similar to that already described inasmuch as the lamp is so constructed that the mercury in the annular space outside the quartz tube will break electrical connection with the leading-in wire when the tube is tilted before contact is made by the body of mercury with the co-operating electrode.

Fig. 8 illustrates a suitable scheme of electrical connection for starting a lamp as described. The cathode and anode are connected respectively by conductors 18 and 19 to a suitable source of direct current. A resistance 20, and if desired a reactance 21, is permanently connected in series with the device and acts as a ballast. Before the device is started a complete circuit is obtained through the conductor 18, the solenoid 22 and the conductors 23 and 19. When the switch is closed, the solenoid 22 is energized and draws up its core 24 which is linked in a suitable manner to the pivoted frame 25 of the lamp. The lamp is tilted by rotation about its pivoted support 26 causing the mercury from the cathode reservoir to flow toward the anode, or vice versa, as the case may be, and thereby supplying a circuit through the lamp. Current flow through the lamp energizes the series solenoid 27 and it pulls up its core, thereby breaking connection between the solenoid 22 and the conductor 23. The lamp, therefore, is returned to its original position by gravity causing the mercury to flow back to the cathode chamber and to break the circuit and strike an arc within the inner tube as already described above. As long as the lamp is running the core of the solenoid 27 remains pulled up but if for any reason the lamp goes out the core re-establishes the circuit of solenoid 22 and the starting operation as above described is repeated.

The form of lamp shown in Fig. 9 is provided in the same manner with an outer envelop 1 and an inner envelop 2 maintained suitably spaced. It is provided with a mercury cathode 4 and a solid anode 10 similarly to the lamp shown in Fig. 4. In this case, however, the lamp is shown as being started by the well-known auxiliary arc or side branch method. A small body of mercury 130

28 contained in a side chamber or pocket is shown, this being made anode when connected to a suitable source of direct current to which the main body of mercury 4 is connected as cathode. When in the well-known manner a potential is impressed upon the main anode 10 and cathode 4 and a side branch arc is struck between the auxiliary anode 28 and cathode 4 by shaking the tube; the main arc is started by the ionization of the space. In this case in order to avoid the striking of the arc at the small exposed portion of the leading-in wire at the junction of the glass wall of the outer envelop and a 15 quartz wall of the inner envelop, a packing of small silica pieces or other refractory material 29 is provided maintained in position around the anode stem by the quartz plate 30 resting upon the top of the inner tube.

What I claim as new and desire to secure by Letters Patent of the United States, is,—

1. In a mercury vapor device, an outer envelop, an open and inner envelop, coöperating electrodes, at least one of which projects into the inner envelop, means for tilting the device to strike an arc between said electrodes, and means at one of the electrodes for preventing the arc from being started in the space between the inner and outer envelops.

2. In a vapor electric device, an outer envelop, an inner tube in communication therewith, an anode and a liquid cathode therefor, the inner envelop being constructed at one or both of its ends to form an insulating barrier when the tube is tilted to break the continuity of the electric circuit through the liquid, outside the inner tube at one electrode before contact is established with the other electrode by the stream of flowing liquid.

3. In a vapor electric device, coöperating electrodes, one at least of which is mercury, a double-walled receptacle, one end at least of which extends downwardly to form a

pocket for the mercury electrode and leading-in conductors for said electrodes, the conductor at the mercury electrode projecting through an opening in the inner wall 50 through which the mercury bodies inside and outside the wall are in communication, the upwardly extending end portion of said inner wall forming a barrier to interrupt electrical contact when the device is tilted of 55 the outer body of mercury before contact is established by the mercury stream with a co-operating electrode.

4. In a vapor electric device, an outer envelop, an open envelop inclosed thereby, coöperating electrodes, at least one of which consists of mercury for the inner envelop, leading-in conductors therefor, the space intervening between the two envelops being proportioned at a mercury electrode so that 60 when the tube is tilted the mercury in the intervening space will break electric contact with the leading-in conductor before electrical contact is made with an electrode of opposite polarity.

5. In a mercury vapor device, an outer envelop, an inner tube located therein and spaced apart therefrom, electrodes therefor one of which consists of mercury, said inner tube only having a trough-shaped channel at the bottom through which mercury 75 may flow.

6. In a vapor electric device, an evacuated inclosing envelop, an open inner arc-inclosing envelop therein, a mercury electrode in said inner envelop communicating with the space intervening between said envelops, and means at the electrode for preventing an arc from starting in the intervening space.

In witness whereof, I have hereunto set my hand this 31st day of March, 1911.

EZECHIEL WEINTRAUB.
